AUTOMOBILE SIGNAL

Filed April 28, 1924

2 Sheets-Sheet 2

Fig. 5.

UNITED STATES PATENT OFFICE.

FREDERICK M. WALZ AND CHARLES J. WALZ, OF BUFFALO, NEW YORK

AUTOMOBILE SIGNAL.

Application filed April 28, 1924. Serial No 709,462.

To all whom it may concern:

Be it known that we, FREDERICK M. WALZ and CHARLES J. WALZ, citizens of the United States, residing at Buffalo, in the county of Erie and State of New York, have invented certain new and useful Improvements in Automobile Signals, of which the following is a specification.

Our invention relates to improvements in automobile signals, such as indicate to a driver of a vehicle following, any intentional change to be made in speed or in the course pursued by the driver of the vehicle having the device applied thereto.

This invention is an improvement on our co-pending application filed June 17, 1922, Serial No. 569,008, and allowed December 12, 1923, and it has for its object to simplify the construction therein disclosed, to reduce the cost of production, and to provide a more compact mechanism with a view of diminishing the size of the signal.

With the above and other objects in view, the invention consists in the novel features of construction, and in the arrangement and combination of parts to be hereinafter described, and more particularly pointed out in the subjoined claims.

In the drawings:

Fig. 1 is a rear elevation of the signal considered as applied to an automobile.

Fig. 2 is an enlarged transverse section taken on line 2—2, Fig. 1, looking in the direction of the arrow crossing said line.

Fig. 3 is a fragmentary longitudinal section taken on line 3—3, Fig. 2, looking in the direction of the arrow crossing said line.

Fig. 4 is a detached perspective view of the signal actuator.

Fig. 5 is an enlarged horizontal section taken on line 5—5, Fig. 1.

Fig. 6 is a longitudinal section taken on line 6—6, of Fig. 2.

Fig. 7 is a detached perspective view of one of the signal members.

Referring to the drawings in detail, the reference numeral 10 designates a casing, which may be of any approved construction and formation. The casing herein shown has a main portion or mechanism chamber 11, and a smaller depending light chamber 12. The main casing comprises a bottom wall 13, end walls 14, 15, a front

wall 16, a rear wall 17, which extends downwardly beneath the bottom 13, and below 55 said bottom is diminished in length and rounded to form the rear wall of the light chamber 12. The front and rear walls 16, 17, respectively, are connected at the top by a crowned top wall 18, which extends 60 from end wall to end wall. The light chamber 12 has a front wall 19 conforming to the lower depending portion of the rear wall 17, and its side and bottom walls, designated by the numeral 20, are formed of a 65 continuous piece whose lower portion is made convex exteriorly and whose upper portions are concaved and merge into the plane of the bottom 13 of the main casing. The bottom 13 of the main casing is provided with a light opening 21 between the mechanism chamber or main casing 11 and the light chamber or casing 12.

Directly above the plane of the bottom 13, an elongated sight opening 22 is formed 75 in the rear wall, and this opening has a pane of transparent glass 23 fitted thereto. In the rear wall of the light chamber or casing, a circular opening 24 is provided in which is fitted a pane of red glass 25. Fitted into the front wall 19 of the light chamber or casing is a bulb socket 26 to which is connected a current conducting wire 27 which leads to a battery or other source of electricity, and secured in said socket is an 85 electric lamp or bulb 28, the same being positioned directly in front of the red pane of glass 25, which latter, taken in conjunction with said lamp or bulb, is adapted to 90 serve as the tail lamp of an automobile.

Arranged within the main casing 11 and fastened to the bottom 13 thereof is a support 29 in the form of a flat plate having a flange 30 at its lower end through which screws are passed to fasten said support to 95 said bottom. Said support extends upwardly from the bottom and has a vertical slot 31 therein midway between its ends. Extending rearwardly from said support are two brackets 32, one being arranged near 100 each end of said support. Positioned between said bracket are two spaced vertically-disposed guides 33 grooved along their inner edges, as at 34. These guides are fastened to the support 29 by means of pins 35, or 105 otherwise, extending rearwardly from said

support, one pin being positioned near the upper end of each guide, and another near the lower end thereof.

Slidably fitted in said guides is a stepped actuator or plate 36, the steps being formed by cutting an irregularly shaped notch 37 into said actuator or plate from the lower edge thereof, the lower edge of said plate at one end thereof and each of the steps 10 forming contact edges, which are designated 38, 39, 40, and 41, respectively, such steps being formed by deepening the notch 37 at regular intervals along the length thereof.

Secured to said actuator plate near its 15 upper edge and preferably centrally between its ends is an angular rod 42, which is constructed to extend forwardly from said plate through the slot 31 in the support 29 and thence at a right angle to extend downwardly parallel with the front surface of said support. Said guide rod is guided in said slot 31 and in a guide lug 43 extending forwardly from said support directly beneath said slot. The lower end of said rod 20 normally projects a short distance beneath said lug and is threaded. A stop collar 44 is applied to said lower threaded end and has a perforated lug 45 extending downwardly therefrom and a similar lug 46 extending laterally.

To the lug 45 a cord or wire 47 is secured, which is directed downwardly through an opening 48 in the bottom 13 and passes around a guide pulley 49 secured in brackets 35 50 fastened to the under side of said bottom directly forward of said opening. Said cord or wire extends forwardly from said pulley and is adapted to be actuated from the driver's seat of an automobile.

40 A retractile spring 51 is provided within the mechanism casing, one end thereof being fastened to the lateral lug 46 at the lower end of said guide rod and the other end to the casing, as at 52. Said spring acts 45 to keep the guide rod 31 and actuator or plate 36 secured thereto in elevated position with the collar 44 bearing against the under side of the guide lug 43.

50 Journaled in the brackets 32 extending rearwardly from the support 29 is a spindle 53 on which all but one of the signaling elements are arranged to swing. In the drawings we have shown four signaling elements and also a shutter adapted to conceal the 55 signaling elements from view through the sight opening 22, said signaling elements and the shutter being normally alined with said sight opening. The shutter is designated by the numeral 54, while the signaling elements are designated 55, 56, 57, 58, respectively. The signaling elements 55, 56 and 57 are pivotally mounted, as will be hereinafter set forth, while the signaling element 58 is a fixed element and comprises a flat plate extending lengthwise and having

a securing flange 59 at its lower end through which screws 60 are passed for fastening said plate to the bottom of the mechanism chamber. This fixed signaling element is the foremost of the series.

70 The shutter 54 comprises a plate somewhat wider and longer than the sight opening 22 in the casing, and this plate is painted black or constructed of some dark material so when positioned in front of the glazed sight opening 22, the interior of the mechanism chamber will have the appearance of being perfectly dark. The exterior of the casing is preferably painted black so that from a distance the shutter will appear as 75 forming part of the casing. At opposite ends of the shutter or plate 54, forwardly extending supporting arms 61 are provided, the terminals of which are loosely fitted over the spindle 53. Positioned between said arms and extending rearwardly from said shutter is an actuating lever 62, which is pivotally mounted on the spindle 53 and has an engaging portion 63 extending forwardly beyond said spindle and underneath the lowermost engaging edge or step 38 of the actuator or plate 36. The signaling elements 55, 56, 57, and 58 are notched, as at 80 85 90 95 100 105 110 115 120 125 130 135 140 145 150 155 160 165 170 175 180 185 190 195 200 205 210 215 220 225 230 235 240 245 250 255 10335 10340 10345 10350 10355 10360 10365 1

engaging portion at the front end of the actuating lever 67 is positioned underneath the third lowest engaging edge or step 40 of the actuator or plate 36, while the engaging portion at the front end of the actuating lever 68 is positioned underneath the uppermost engaging edge or step 41 of said actuator or plate 36.

On the ends of the spindle 53 and bearing 10 against the outer sides of the arms 61, collars 73 are fastened and like collars 74 are fastened to said spindle and bear against the inner sides of the innermost arms 65 extending rearwardly from the signaling element 57. Between each of the arms 61 and the adjacent arms 65 projecting from the signaling element 53, and also between the arms 65 of the several signaling elements, spacing sleeves 75 are arranged, said sleeves 20 being mounted on the spindle 53. The actuating arms 62 and 68 are spaced from the brackets 32 by comparatively long sleeves 76, and the several actuating arms are spaced from each other by spacing sleeves 77.

25 Due to the fact that the actuating levers are in horizontal alinement and the engaging edges or steps of the actuator or plate 36 are in different horizontal positions, the lowering of said actuator plate will cause it to be engaged successively with the actuating levers 62, 66, 67, 68. With all parts in normal positions, the signaling elements are disposed one in front of the other with the shutter member in rear of said signaling elements so as to conceal the same from the rear. While we have shown four signaling elements, the number of these may be changed, if desired, depending on the number of different signals which it is desired to give with the device. It is, of course, understood that the actuator or plate 36 will be provided with a number of actuating edges or steps conforming to the number of pivoted plates used as a shutter member and signaling elements.

As now arranged it is intended that the foremost or fixed signaling element 58 shall bear the word "Right"; the signaling element 57 directly in rear and spaced therefrom, the word "Left"; the signaling element 56 directly in rear of the left signaling element, the word "Stop," while the signaling element 55 between the stop signaling element and the shutter may bear the word 50 "Caution"; which caution signaling element is to be used when it is desired to reduce the speed of the automobile to which the device is applied, or when it is desired to caution the driver of an automobile in rear, preparatory to giving a further signal, such as "Stop," "Right" or "Left."

60 The actuator or plate 36 and the guide rod 31 with necessary adjuncts may be considered the actuating means or mechanism of the device, while the cord or wire 47 with its

pulley 49 and other parts associated therewith, may be considered the manipulating mechanism. When drawing upon the cord or wire, the actuating mechanism will be operated, due to the fact that the guide rod 70 31 will be moved downwardly against the action of the spring 51 connected thereto, and due to the connection of this guide rod with the actuator or plate 36, said plate will be lowered. By suitable means at the front 75 end of an automobile, the amount of pull on the cord or wire 47 can be easily controlled. Consequently, when it is desired to give notice that it is the intention of the driver to reduce speed, or later give another signal, 80 said cord or wire will be drawn forwardly a predetermined and known distance, whereupon the guide rod 31 will be drawn downwardly, with the result that the actuator or plate 36 will move downwardly and cause 85 the lowermost engaging edge or step 88 thereof to lower the forward or engaging portion of the actuating lever 62 on the shutter. This will cause the shutter to be swung from its normal or lowered position, 90 shown in full lines in Fig. 2, to its elevated position, or that shown in dotted lines; thus exposing the rearmost signal element 55 bearing the word "Caution" through the sight opening. This will bring the next 95 engaging edge or step 39 of the actuator or plate 36 in contact with or in close proximity to the engaging portion of the actuating lever 66 on said caution signaling element, but no actuation of said signaling element takes place. If, however, it is desired to expose the signaling element 56 bearing the word "Stop", said cord or wire 47 will be drawn forwardly to a greater extent, 100 with the result that said engaging edge or step 39 will depress the engaging portion of the actuating lever 66. This will cause the rearmost or caution signaling element 55 to be elevated in the same manner as the shutter, thereby exposing the signaling element 56 105 bearing the word "Stop" through the sight opening. 110

When the shutter and the caution signal element 55 are swung into elevated position, the next engaging edge or step 40 on the actuator or plate 36 will be in contact with, or close proximity to, the engaging portion at the front end of the actuating lever 67 extending forwardly from the stop signaling element 56. If, therefore, the cord or wire 47 is drawn forwardly to a 120 somewhat greater extent, said engaging edge or step 40 will depress the engaging portion of said actuating lever 67 and cause the stop signaling element to be swung upwardly, thereby exposing the signaling element bearing the word "Right" through the glazed sight opening 22.

When the shutter 54 and the signaling elements 55, 56 are elevated, the uppermost engaging edge or step 41 of the actuator or 130

plate 36 is in contact with, or in close proximity to, the engaging portion at the front end of the actuating lever 68 extending forwardly from the left signaling element 57, and when drawing upon the cord or wire to a somewhat greater extent, said engaging edge or step 41 will cause the engaging portion of said actuating lever to be depressed so as to elevate the foremost movable 10 or right signaling element and expose the immovable or rigid signaling element 58 bearing the word "Right" through the glazed sight opening.

It is of course to be understood that the 15 cord or wire need not necessarily be moved step by step since if the signaling element bearing the word "Left" is to be exposed through the glazed sight opening, the cord or wire will be drawn upon to an extent to cause the shutter and the two rearmost signaling elements 55 and 56 to be swung upwardly in succession, and during a continuous downward movement of the actuator or shutter plate, this being also the case 25 when any other signal is to be given.

It is of course understood that the spring 51 connected to the guide rod 42 serves at all times to return the actuator or plate 36 to its normal or elevated position and retain 30 the same in such position.

With a view of drawing the shutter and movable signaling elements downwardly after being elevated and the actuator or plate 36 is elevated, a retractile spring 78 is provided, which is secured at its lower end to the bottom 31 of the casing and with its upper end one of the arms 61 extending forwardly from opposite ends of the shutter, as at 79, and due to the fact that the 35 actuating lever 62 of said shutter extends forwardly therefrom over the top of the signaling elements, said lever will cause all elevated movable signaling elements to be lowered with said shutter. Said spring 78 also serves to hold the lower edges of said 40 shutter and movable signaling elements in contact with the bottom 13 of the casing and prevent rattling when the vehicle to which the device is applied is traveling over rough 45 or uneven roads.

By reason of the opening 21 in the bottom 13 of the mechanism chamber or main casing, the rays of light from the lamp 28 in the depending light chamber 12 are directed upwardly and serve to illuminate any of the signaling elements that may be exposed by manipulation of the cord 47 so that the word "Caution," "Stop," "Left" or "Right," depending on the manipulation of the device, will be seen through the glazed sight opening 22.

Having thus described our invention, what we claim is:

1. An automobile signal having a plurality of signaling elements arranged one in

front of another, a reciprocating actuating element to successively engage said signaling elements, and a single manipulating element for actuating said reciprocating actuating element for selectively displaying any 70 of said signaling elements.

2. An automobile signal having a rigid signaling element and a plurality of pivotally-mounted signaling elements arranged one in front of another and positioned in rear of said rigid signaling element, a shutter member for concealing said signaling elements, and means for manipulating said shutter member and displaying the desired 75 signaling element, said means including a reciprocating member successively engaging said shutter member and said pivotally-mounted signaling elements, and a single manipulating element for actuating said reciprocating member.

3. An automobile signal, comprising a casing having a sight opening, a shutter member normally exposed through said sight opening, a plurality of signaling elements concealed by said shutter member, and reciprocating means for actuating said shutter member and displaying any one of said 90 signaling elements.

4. An automobile signal, comprising a 95 casing having a sight opening, a shutter member normally exposed through said sight opening, a plurality of signaling elements normally concealed by said shutter member, and means including a vertically reciprocating element adapted for successive engagement with said shutter member and signaling elements to successively expose said signaling elements through said sight opening.

5. An automobile signal, comprising a casing having a sight opening, a plurality of pivotally-mounted spaced signaling elements arranged in parallelism, a single stepped actuating member adapted for reciprocating movement and in operative relation to all of said signaling elements, and a manipulating element for manipulating said actuating member to cause the same to successively expose said signaling elements. 110

6. An automobile signal, comprising a casing having a sight opening, a plurality of signaling elements adapted to be displayed through said sight opening, a stepped actuating member arranged for reciprocating movement and in operative relation to said signaling elements, each of said signaling elements being adapted to be operated during a portion of the movement of said actuating member, and a single element for moving said actuating member to any desired extent.

7. An automobile signal, comprising a casing having a sight opening, a plurality of signaling elements arranged one in front 120

- of another and adapted to be displayed successively through said sight opening, an actuating member having engaging steps in different horizontal planes and adapted for 5 vertically reciprocating movement, each actuating step being operatively related to one of said signaling elements, and means for moving said actuating member to any desired extent.
- 10 8. An automobile signal, comprising a casing having a sight opening, a plurality of signaling elements normally in line with said sight opening and arranged for movement consecutively, a depending tail-light adapted 15 to direct rays of light upwardly against said signaling elements when exposed through said sight opening, and means for selectively displaying said signaling elements.
9. An automobile signal, comprising a 20 plurality of signaling plates, each plate having forwardly-extending arms pivotally mounted and an actuating lever, and a vertically reciprocated stepped member adapted to have its steps successively actuate each of 25 said actuating levers.
10. An automobile signal, comprising a casing having a sight opening, a series of pivoted flat signaling elements arranged one in rear of another, an actuating lever for 30 each signaling element pivotally secured between its ends, a vertically reciprocating stepped actuator adapted to have its steps successively engage said actuating levers at one side of their pivotal points, means for 35 manually lowering said actuator, and means for automatically elevating said actuator.
11. An automobile signal, comprising a casing having a sight opening, a plurality of 40 signaling plates arranged one in rear of another and provided with forwardly-extending arms at opposite ends pivotally mounted at their front ends, each plate having a pivoted actuating lever whose pivot is coincident with the pivots of said arms, a reciprocating member provided with lever-engaging parts arranged in different planes to cause successive actuation of said actuating levers, and means for actuating said 45 reciprocating member to any desired extent.
12. An automobile signal, comprising a casing having a sight opening, a plurality of signaling plates arranged one in rear of another and each having forwardly extending 50 arms at opposite ends pivotally secured, the arms of said signaling plates having their axes coincident, forwardly-extending actuating levers on said plates pivotally secured between their ends in alinement with the pivots of said arms, a vertically-reciprocating actuating plate having an irregular shaped notch extending inwardly from its lower end to provide lever-engaging portions in different horizontal planes, each lever-engaging portion being adapted to engage one 55 of said actuating levers, manual means for lowering said actuating plate to any desired extent, and means for returning said actuating plate to normal position.
13. An automobile signal, comprising a 60 casing having a sight opening, a signaling element in fixed position within said casing forward of said sight opening, a plurality of movable signaling elements between said fixed signaling element and said sight opening, each of said movable signaling elements having forwardly-extending arms at opposite ends pivotally mounted at their forward ends with the pivots of all of said arms in alinement, actuating levers extending forwardly from said movable signaling elements between the arms thereof and pivotally mounted between their ends in alinement with the pivots of said arms, a vertically-reciprocating actuating plate having 65 stepped lever-engaging portions, each lever-engaging portion to engage a single actuating lever, an angular guide rod connected to said actuating plate, a spring connected to said guide rod to hold the same elevated, 70 and a manipulating cord connected to said guide rod to lower the same to any desired extent.
14. In an automobile signal, a plurality of movable signaling elements having parts 75 projecting therefrom, a vertically-reciprocating actuating plate having stepped engaging portions, the steps of which are arranged in different horizontal planes and adapted to successively engage said projecting parts for moving said signaling elements, means for lowering said actuating plate to any desired extent, and means for 80 automatically returning said actuating plate to elevated position.
15. An automobile signal, comprising a plurality of pivoted signaling elements having parts projecting therefrom, a reciprocating member provided with engaging parts spaced different distances from the 85 projecting parts of said signaling elements and adapted to successively engage said projecting parts at different portions of the movement of said reciprocating member in one direction, means for moving said reciprocating member in said direction to any desired extent, and means for automatically moving said reciprocating member in the opposite direction.
16. An automobile signal, comprising a 90 casing having a sight opening, a plurality of signaling plates arranged one in rear of another and normally in line with said sight opening, said plates being provided with pivotally mounted actuating elements, a reciprocating member adapted to successively engage said actuating elements and cause said signaling plates to move in one direction, and means to automatically retain said signaling plates in normal position and to 95

return the same to normal position after being moved by said reciprocating member.

17. An automobile signal, comprising a casing having a sight opening, a support within said casing having a vertical slot therein, spaced vertical guides supported by said support and in parallel relation thereto, an actuating plate guided for vertical movement in said guides and having stepped lever-engaging portions arranged in different horizontal planes, a plurality of signaling elements in rear of said support having actuating levers extending forwardly therefrom, said levers being adapted to be successively engaged by the stepped lever-engaging portions of said actuating plate, a guide rod secured at one end to the upper end of said actuating plate and extending forwardly through the slot of said support and thence downwardly parallel with said support, a guide element on said support in which the lower end of said rod is guided, a manipulating cord secured to the lower end of said rod and adapted to draw the same downwardly to any desired extent, said actuating plate being drawn downwardly with said rod to successively actuate said signaling elements, and means to return said rod, actuating plate and signaling elements to normal position after releasing said cord.

18. An automobile signal, comprising a casing having a sight opening, a plurality of movable signaling elements in front of said sight opening having forwardly ex-

tending actuating levers pivotally secured between their ends to provide engaging portions in advance of the pivotal points thereof, a support within said casing in front of said signaling elements comprising a plate extending upwardly from the bottom of said casing and having a vertical slot at its upper end, a pair of spaced vertical guides in rear of said support and carried thereby, an actuating plate guided for movement in said guides and having engaging portions in different horizontal planes to successively engage the engaging portions of said actuating levers for actuating said signaling elements, a guide rod in front of said support having a rearwardly-extending portion at its upper end passed through the slot of said support and fastened to said actuating plate, guide means on said support by means of which the slot in said support said guide rod is guided, said guide rod having a collar secured to its lower end adapted to bear against said guide means, a spring to hold said guide rod elevated and to draw said collar against said guide means, and a flexible manipulating element secured to said collar and extending downwardly through the bottom of said casing and thence forwardly for conveniently manipulating the signaling elements from a distant point.

In testimony whereof we affix our signatures.
